UNITED STATES PATENT OFFICE

JULIUS C. BUZZELLI, OF BEVERLY, NEW JERSEY, ASSIGNOR TO RADIO CORPORATION OF AMERICA, INC., A CORPORATION OF DELAWARE

METHOD OF MARKING RECORDS

Application filed December 18, 1931. Serial No. 581,812.

My invention relates to a method of applying markings to articles and, more particularly, to a method of applying indicia to phonograph record tablets.

5 Various methods of applying titles, identification numerals and the like to record tablets are employed. One of the most commonly used is the pasting of a paper label, with the desired markings printed thereon, 10 upon the unrecorded area usually left at the center of a finished record.

Another method with which I am familiar is to roughen or mat the unrecorded, smooth surface left at the center of the finished 15 record tablet. As this matted surface will "take" ink, it is possible to print the markings directly thereon.

The above methods are objectionable in that they require considerable time and a 20 number of operations to be performed.

Another inherent disadvantage in the methods above noted is the possibility of applying the wrong label or printing stamp to the records. This would necessitate the 25 scrapping of the records or else the correction of the error, which, obviously, consumes additional time and also adds to the production cost.

It is, accordingly, the primary object of 30 my invention to provide a method of marking phonograph record tablets that will not be subject to the disadvantages pointed out above.

Another object of my invention is to provide 35 a method of marking phonograph record tablets by one simple operation, whereby any number of records made from a master record are identically marked.

Another object of my invention is to provide 40 a method of marking phonograph record tablets, whereby the markings are impressed simultaneously with the pressing of the sound grooves in the record material.

Other objects and advantages will herein- 45 after appear.

In carrying out my invention, I have found 50 that by stamping suitable data such as numerals, letters or other characters with ordinary lithographers ink upon the smooth unrecorded surface left at the center of the

original wax record, upon metallizing the record electrolytically in the usual way, the ink markings will give rise to roughened or matted impressions in the metal coating. The matted impressions, in turn, produce 55 slightly elevated matted markings upon the finished records, when they are moulded, by pressing between matrices in a manner well understood by those skilled in the art.

The invention will, however, be more 60 clearly understood from the following description when taken in connection with the accompanying drawing, in which:

Fig. 1 is a view in perspective illustrating 65 a step in my method of record marking, and

Fig. 2 is a plan view of a finished record tablet with identification markings produced thereon by my improved method.

Referring now to the drawing, wherein like numerals refer to like parts, there is 70 shown in Fig. 1 an original wax record 10 having recorded thereon the sound grooves 11. As is customary, I provide an unrecorded area 12 of a size suitable to accommodate the title or such other indicia as it 75 may be desired to place upon the finished record tablets.

Within the unrecorded space 12, which has a smooth surface, I print suitable markings 13. I have found that an ordinary rubber 80 stamp and lithographer's ink are suitable for this purpose, but it is to be understood that other inks or paints might be used with equally satisfactory results and that the markings may be applied in any suitable way 85 other than by a rubber stamp.

After the markings have been stamped upon the record 10 in the above described manner, the ink is allowed to dry and the record surface is then metallized in the usual 90 manner.

In Fig. 1 of the drawing, I have illustrated the metal covering or commonly called master matrix, 14 as it appears after it has been removed from the surface of the original 95 record 10, with the ink markings 13 as having made matted depressions 15 therein. In contrast to the matted depressions 15, the surface 16, on which they have been impressed and which corresponds to the surface 12 on 100

which the numerals 13 were stamped, is relatively smooth.

From the master matrix 14, a so called master metal mould is electrolytically formed, and from the master mould, any desired number of record pressing matrices are made, likewise by electro-deposition.

It will be apparent from the method described above, that the working surfaces of the master mould and the pressing matrices are, respectively, counterparts of the surface of the original wax record 10 and the surface of the master matrix 14, and for this reason, they have not been illustrated in the drawing. However, it will readily be understood from the foregoing description that the record pressing matrices have on the surface thereof matted depressions in addition to the usual grooves which are negative to the sound grooves on the original wax record.

From these matrices, the final finished record tablets are pressed, and I have found that the matted depressions on the matrices produce on the record tablet raised matted markings which, in outline, are a counterpart of the markings which were stamped on the master wax record 10.

Fig. 2 of the drawing shows a finished record tablet 17 on which numerals 18 have been reproduced by the method described above.

The numerals 18 are slightly raised and have a matted surface and, although they are of the same material and color as the finished record tablet, they stand out quite clearly in contrast to the surrounding surface 19 which is smooth and glossy.

From the above description, it will be apparent that the legibility of the markings 18 depends on the reflected light from the surrounding surface 19 in contrast to the scattered light reflected from the matted surface of the markings.

It will, therefore, be readily understood that I may reverse these conditions; that is, in preparing the master record, I may arrange to have the markings as smooth open spaces within an inked background. This would produce, upon the finished record tablets, smooth, light reflecting indicia upon a matted background.

Although I have shown and described a preferred method of applying my invention to the marking of record tablets, it is obvious that my invention is not necessarily limited to the reproduction of markings, designs and the like upon phonograph records and that the method comprising my invention is equally applicable to the placing of markings upon other articles. Hence no unnecessary limitations are to be understood except as required by the appended claims when construed in the light of the prior art.

I claim as my invention:

65. 1. In the method of preparing a record

matrix, the steps which consist in applying markings upon a master record, and causing a metallic coating to be deposited upon the surface of said master record.

2. In the method of preparing a record matrix, the steps which consist in applying markings with an inked stamp to a master record and causing a metallic coating to be deposited upon the surface of said master record. 70

3. In the method of preparing a record matrix, the steps which consist in stamping markings upon a master record, and causing a metallic coating to be deposited upon the surface of said master record. 75

4. In the method of preparing a record matrix, the steps which consist in stamping markings upon a master record with a resilient stamp, and causing a metallic coating to be deposited upon the surface of said master record. 80

5. In the method of preparing a record matrix, the steps which consist in stamping markings upon a master record with an inked, resilient stamp, and causing a metallic coating to be deposited upon the surface of said master record. 90

6. The method of forming a record matrix which comprises placing markings upon a master record provided with sound grooves, 95 and thereafter electroplating both said grooves and said markings in a continuous operation.

7. The method as set forth in claim 6, wherein said grooves and said markings are 100 simultaneously electroplated.

In testimony whereof, I have hereunto subscribed my name this 14th day of December, 1931.
